CLAIM

The ornamental design for a fender and wheel with integrated lock, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a fender and wheel with an integrated lock;

FIG. 2 is a right view thereof;

FIG. 3 is a left view thereof;

FIG. 4 is a rear view thereof;

FIG. 5 is a top view thereof;

FIG. 6 is a bottom view thereof; and,

FIG. 7 is a front view thereof.

The broken lines are included for the purpose of showing environmental portions of the fender and wheel with an integrated lock and form no part of the claimed design.

1 Claim, 5 Drawing Sheets
